RACK FOR UTILITY, TELEPHONE AND POWER
CABLES OR THE LIKE

Lyle H. Mathews, 2712 W. Porter St. 2,
Fullerton, Calif. 92631

Filed July 29, 1971, Ser. No. 167,540

Term of patent 14 years

Int. Cl. D8—08

U.S. Cl. D8—230

Fig. 4

Fig. 2

Fig. 3

Fig. 1

FIG. 1 is an isometric view of a rack for utility, telephone and power cables or the like showing my new design;

FIG. 2 is a front elevation view thereof;

FIG. 3 is a side elevation view thereof; and

FIG. 4 is a top plan view thereof.

The back of the present rack for utility, telephone and power cables or the like is flat for contact with and attachment to a wall.

I claim:

The ornamental design for a rack for utility, telephone and power cables or the like, as shown and described.
